UNITED STATES PATENT OFFICE.

HARRY E. KHOURY, OF NEW BEDFORD, MASSACHUSETTS, ASSIGNOR TO KHOURY
WARP STOP MOTION, INC., A CORPORATION OF MASSACHUSETTS.

WARP STOP MOTION.

Application filed September 21, 1926. Serial No. 136,832.

The present invention relates to warp stop motions for looms, and has to do with stop motions of the general type disclosed in my Patent No. 1,527,196, granted February 24, 5 1925.

An object of the present invention is to provide a stop motion which is simple in construction, having a relatively small number of operative parts, and is effective to 10 stop the loom without imposing a strain upon the heddles and detector bar.

It has been found that in the operation of this type of stop motion, there is a tendency to twist or bend the heddles when one 15 or more of the same lock the detector bar, the strain of throwing the shipper lever or otherwise stopping the loom being transmitted to the heddles which lock the bar. Attempts have been made to overcome this 20 objection by associating with the heddle adjacent the detector bar, an abutment element, which serves to stiffen the heddles. This expedient is objectionable for various 25 reasons, among others, that it complicates the construction of the harness frame, and is not always effective.

The present invention seeks to avoid this objection by providing a warp stop motion, in which there is substantially no strain imposed upon either the detector bar or the 30 heddles when the loom is stopped.

A further object of the invention is to provide a mechanism which may be adjusted, in order to insure immediate stopping of the loom, should a warp thread break, and to provide for accurate operation 35 of the various parts.

The foregoing and other objects of the invention which have more to do with the 40 details of the structure, will become obvious as the description proceeds in connection with a preferred embodiment of the invention shown in the accompanying drawings, wherein:—

45 Figure 1 is a side elevational view, showing a portion of the loom and its frame in dotted lines.

Figure 2 is a front elevational view, showing 50 more clearly the relation of the various parts.

Figure 3 is a fragmentary horizontal sectional view on the line 3—3 of Figure 2,

Figure 4 is a vertical section on substantially the line 4—4 of Figure 2.

Figure 5 is a vertical sectional view 55 through a harness frame, showing the relation of the parts and the normal position of the detector bar,

Figure 6 is a view similar to Figure 5, showing the detector bar locked when a heddle falls,

Figure 7 is a vertical sectional view taken through the brackets, showing the construction of one of the contact elements.

Figure 8 is a vertical section on the line 85 8—8 of Figure 9,

Figure 9 is a fragmentary sectional view, showing the construction at one end of the detector bar,

Figure 10 is an elevational view of a harness frame, showing a somewhat modified construction, and

Figure 11 is an end view looking toward the left in Figure 10.

Referring to the drawings for a more detailed description, 10 (Fig. 1) indicates conventionally a portion of a loom provided with a plurality of harness frames 11, which have metallic side portions 12 connected by top and bottom cross pieces 14. The frame 70 is reinforced by cross bars 14, which extend through the heddles 15. The latter have at their upper ends, openings 16 to receive a cross bar 14, and also a detector bar 17, the latter being angular in cross section, in order to fit within a notch 18 at the upper 75 end of the slot 16, and there be held against detecting movement, which, in the present instance, is of rocking character. In other words, the detector bar 17 is adapted to oscillate or rock about its longitudinal axis, and it is provided with the rib 19, adapted to fit within the notch 18 when one of the heddles falls, because of a broken or slack warp thread.

The detector bar is normally in the position illustrated in Figures 5 and 8, and it is 80 yieldingly maintained in this position by means of an encircling spring 20 (Fig. 9), which has one end 21 fastened to the harness frame, and its other end 22 extending through a slot 23 in a sleeve 24, which is 85 fixedly secured upon the end of the detector bar by means of a set screw 25. The movement of the detector bar in a clockwise direction, as viewed in Figures 5 and 8, may 90 be limited, as by means of a collar 26, fastened by means of a set screw 27 on the de-

tector bar, and having a circumferentially cut-away portion 28, within which fits a stop finger 29 upon a stop plate 30. One end of the slot or cut-away portion 28 provides 5 a shoulder 28', which is normally held against the finger 29 (Fig. 8) by means of the spring 20. In this position, the rib 19 upon the detector bar is out of alignment with the notches 18 in the heddles, and as 10 the harness frame rises, carrying the detector bar, the rib 19 will not fit within the heddle notches 18.

The sleeve 24 has a projecting finger 31 adapted to engage an element upon the loom 15 as the harness frame moves, and thus there is imparted to the detector bar its detector movement, which, in the present instance, is a rocking or oscillatory one. The sleeve has also a second projecting finger 32, which fits 20 through an opening 33 in a movable member 34 mounted at 35 upon the harness frame for pivotal movement under the influence of the detector bar. As will be understood, the member 34 rocks on its supporting pin 25 35 under the influence of the detector bar, and thus has a movement relative to the detector bar, and also simultaneously with the latter. Furthermore, when the detector bar is returned to its normal position by the 30 coil spring 20, the member 34 is actuated from the same through the detector bar. This member 34, as will later be described, is normally arranged out of the path of a yielding member upon the loom frame, but 35 when a fallen heddle locks the detector bar against movement, the member 34 is held in the path of such yielding element, and thus effects stopping of the loom.

Referring now to the parts of the mechanism which co-operate with the projecting finger 31 and the movable member 34, there 40 is positioned upon the loom frame, a bracket 36 secured to the frame, as by means of bolts 37. The bracket has an upstanding portion 45 38 which carries a lever 39 pivoted at 40, upon the bracket. The lever is held in a substantially horizontal position (Fig. 2) by means of a coil spring 40 secured by a screw stud 41 and lock nuts 42 to one end of the 50 lever. At the other side of its fulcrum 40, the lever carries a plurality of contact elements 43, corresponding in number to the number of harness frames or projecting fingers 31 (in the present instance two, with 55 55 which they co-operate to rock the detectors as the harness frames descend, and carry the fingers 31 against the top surfaces of the detector elements. Each detector element (Fig. 4) is substantially T-shaped, having a top cross head 43' and a screw-threaded stem 44, which has fitted thereon an adjusting nut 45 arranged between upper and lower webs 46, 47 (Fig. 7) of the bracket. As will be understood, rotation of the nuts 60 45 upon the stems of the contact elements

will adjust the latter vertically. These nuts may be locked against accidental rotation by means of a locking device in the form of a flattened pin 49, extending between the webs 46, 47 of the bracket behind the lock 70 nuts. The locking device 49 has terminal portions 50, which normally gravitate to the substantially vertical position illustrated in Fig. 2, and thus maintain the locking device in the position more clearly shown in Fig. 7. 75 In this position of the locking device, there is not sufficient clearance between the same and the nuts to permit the same to be rotated. However, by simply turning the locking device to bring the ends in a horizontal plane, the nuts may be freely rotated to adjust the contact members vertically.

It will be understood that as the harness frames descend, the fingers 31 upon the detector bars engage the top surfaces of the contact elements, and the parts are rocked from the position illustrated in Fig. 5 to that illustrated in Fig. 6. Should there be a fallen heddle in any harness frame as the 80 detector bar is thus rocked, it will immediately slip downwardly, so that its notch 18 interfits with the rib 19 upon the detector bar. As the harness frame rises, the fallen heddle retains the detector bar against 85 return movement to the position illustrated in Fig. 5, to which position it normally tends to return under the influence of the spring 20. The detector bar is thus retained in the position illustrated in Fig. 6 by the locking 90 detector bar, and as it rises, it may interlock with the remainder of the heddles.

It will be further understood that the rocking movement of the detector bar imparts an oscillating movement to the movable member 34 (Fig. 9) upon the harness frame, and when the detector bar is locked, as the heddle frame ascends, the member 34 is held in the vertical position illustrated by the dotted lines in Fig. 4.

At the upper end of the bracket portion 38, there is pivoted a second lever 52 by means of the fulcrum pin 53. One end of the lever 52 carries a plurality of contact elements 54, having threaded stems 55, upon which fit adjusting nuts 56, the latter being arranged between webs 57, 58 of the bracket. The nuts 56 are held against accidental rotation by means of a locking device 59 similar to the locking device 49 of the lower lever 39. Each contacting element has an outwardly projecting finger 60, which is arranged to one side of the movable element 34 upon the harness frame when the detector bar is in its normal or unlocked position 115 (Fig. 5) as the harness frame rises. The relative positions of these parts is illustrated clearly in Fig. 4. However, when the detector bar is locked by the heddles, the upper 120 forked end 34' of the member 34 is posi- 125 130

tioned in the same vertical plane with the finger 60, and as the harness frame rises, will engage the finger 60 and raise the end of the lever 52.

5 The lever 52 may be connected in any suitable manner with the shipper lever, so as to effect stopping of the loom. A preferred connection illustrated in the drawings consists of the pitman link 62 depending from 10 the lever 52 and connected with an intermediate lever 63 pivoted at 64 upon a tailpiece 65 of the bracket 36. This lever 63 is formed in two parts, to permit of longitudinal adjustment, having a pin and slot connection 66, and its rear end 67 carries a depending link 68, which is secured to a lever 69 mounted upon a block 70, which is in turn secured, by means of a set screw 71, upon a reciprocable rod 72. The rod 72 may be 20 mounted for sliding movement in a frame bearing 73 (Fig. 1), and at its other end may be secured to a lever 74 which engages the shipper lever 75. This connection between the lever 52 and the shipper lever 25 forms no part of the present invention, since it is disclosed in a co-pending application, Serial No. 120,378, filed July 6, 1926. The lever 69, in its normal position, is arranged out of the path of a knock-off element 77, which may be positioned upon any moving power operated part of the loom, such as the lay L. When one end of the lever 52 is raised by a locking detector rod, this results also in the raising of the end 69' 35 (Fig. 1) of the lever 69, bringing the same into the path of the knock-off element 77, and effecting stopping of the loom.

An important feature of the invention is the arrangement of the parts whereby the 40 loom is stopped, without imposing upon either the detector bar or the heddles a twisting or torsional strain. When a fallen heddle locks the detector bar, this maintains the movable element 34 (Fig. 4) in a substantially vertical position (see the dotted line 45 position of Fig. 4), and in this position it engages the finger 60 on the top lever 52 as the harness frame rises. Any impact or strain resulting from such engagement is 50 transmitted directly to the fulcrum support or pivot 35 of the member 34. There is no tendency to rotate the detector bar in a clockwise direction (Fig. 4), due to the vertical position of the member 34, and such 55 movement is also limited by means of the shoulder 28" on the collar 26. Thus the collar 26 and the member 34 serve to receive all strain incident to the operation of the stop mechanism, and there is no necessity for reinforcing the heddles or providing abutment 60 means to prevent twisting or distortion of the same in the operation of the stop mechanism.

Referring to Figs. 10 and 11, there is 65 shown a somewhat modified construction, in

which the single harness frame 11' is provided with a plurality of detector bars 19'. The two detector bars are arranged one slightly above the other, and are connected at one end of the frame by means of short 70 arms 80, which extend vertically and are interconnected by means of a link 81. At the opposite side of the harness frame, one of the detectors is extended to carry a sleeve 24', corresponding to the sleeve 24 of Fig. 75 9, this sleeve being provided with the projecting finger 31' and a second finger 32', which operates a movable member 34', pivoted at 35' upon the harness frame. This construction is otherwise no different from 80 the form previously described. However, it will be understood that it is useful in connection with a plurality of banks of heddles arranged within a single harness frame. Each bank of heddles will be provided with 85 a detector bar associated therewith, and adapted to be locked by the heddles when a warp thread breaks or slackens.

I claim:

1. In a warp stop motion for looms, the 90 combination with a heddle frame having a series of heddles supported by warp threads, of a movable detector bar mounted in the heddle frame, the heddles being formed to engage and lock the bar against movement 95 when a warp thread breaks, and means adapted to give the bar a detecting movement as the heddle frame moves and effective to stop the loom when the bar is locked against movement, said means comprising a 100 bracket positioned upon the loom frame, an element on said bracket adapted to impart a detecting movement to the bar, a yielding element movable through the bar when the latter is locked, and means mounted for 105 movement with the heddle frame and movable with the detector bar serving to engage said yielding member only when the detector bar is locked.

2. In a warp stop motion for looms, the 110 combination with a heddle frame having a series of heddles supported by warp threads, of a movable detector bar mounted in the heddle frame, the heddles being formed to engage and lock the bar against movement 115 when a warp thread breaks, and means adapted to give the bar a detecting movement as the heddle frame moves and effective to stop the loom when the bar is locked against movement, said means comprising a 120 bracket positioned upon the loom frame, an element on said bracket adapted to impart a detecting movement to the bar, a yielding element movable through the bar when the latter is locked, and means mounted for 125 movement with the heddle frame and movable relative to the detector bar and also with the latter during its detecting movements serving to engage said yielding element only when the detector bar is locked.

3. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to give the bar a detecting movement as the heddle frame moves and effective to stop the loom when the bar is locked against movement, said means comprising a bracket positioned upon the loom frame, an element on said bracket adapted to impart a detecting movement, a yielding element movable through the bar when the latter is locked, and means on the heddle frame movable by the detector bar serving to engage said yielding member only when the detector bar is locked, said means serving to actuate said yielding member without placing a torsional strain upon the heddles.

4. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to give the bar a detecting movement as the heddle frame moves and effective to stop the loom when the bar is locked against movement, said means comprising a bracket positioned upon the loom frame, a yielding element on said bracket adapted to impart a detecting movement to the bar, a second yielding element movable through the bar when the latter is locked, and means mounted for movement with the heddle frame and movable by the detector bar and relative thereto serving to engage said last mentioned yielding member only when the detector bar is locked, said means serving to actuate said yielding member without placing a torsional strain upon the heddles or detector bar.

5. In a warp stop motion for looms comprising a heddle frame having mounted therein a movable detector bar adapted to be locked against movement by a fallen heddle, and loom stopping means effective only when the detector bar is locked comprising contact means on the loom comprising a vertically adjustable element having a threaded stem, a bracket supporting said element and receiving said stem, an adjusting nut on said stem, and means on the bracket for locking said nut against accidental rotation.

6. In a warp stop motion for looms comprising a plurality of heddle frames each having mounted therein a movable detector bar, means on the loom, effective to stop the loom when the bar is locked by a fallen heddle and to rock said bars, said means comprising a bracket on the loom frame, a plu-

rality of vertically adjustable contact elements on said bracket each having a threaded stem fitting in the bracket, a nut on each stem adapted to effect vertical adjustment of the contact element, and means on the bracket adapted to lock a plurality of said nuts against accidental rotation.

7. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked by a fallen heddle, said means comprising a member mounted for movement with the heddle frame and movable relative to the detector bar, means on the loom adapted to be engaged by said member through movement of the heddle frame and actuate said bar and member as the heddle frame moves in one direction whereby the bar is given its detecting movement, and an element engageable by said member, only when the detector bar is locked and as the heddle frame moves.

8. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked by a fallen heddle, said means comprising a member mounted for movement with the heddle frame and movable relative to the detector bar, means on the loom adapted to be engaged by said member through movement of the heddle frame and to actuate said bar and member as the heddle frame moves in one direction whereby the bar is given its detecting movement, and an element engageable by said member as the heddle frame moves in the opposite direction, only when the detector bar is locked.

9. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked by a fallen heddle, said means comprising a member mounted for movement with the heddle frame and movable relative to the detector bar, means on the loom adapted to actuate said bar and member as the heddle frame moves in one direction whereby the bar is given its detecting movement, and an element engageable by said member as the heddle frame moves in

the opposite direction, said element being actuatable without placing a torsional strain upon the heddles or detector bar.

10. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked, said means comprising a member mounted for movement with the heddle frame and pivotal movable relative to the detector bar, and also with the latter during its detecting movement, means on the loom frame adapted to be engaged as the heddle frame moves in one direction to impart a detecting movement to said bar and to move said member, and an element on the loom frame adapted to be engaged by said member as the heddle frame moves.

11. In a warp stop motion for looms, the combination with a heddle frame having a series of heddles supported by warp threads, of a movable detector bar mounted in the heddle frame, the heddles being formed to engage the lock bar against movement when a warp thread breaks, and means adapted to stop the loom when the detector bar is locked, said means comprising a member mounted for movement with the heddle frame and pivotal movable relative to the detector bar, and also with the latter during its detecting movement, means on the loom frame adapted to be engaged as the heddle frame moves in one direction to impart a detecting movement to said bar and to move said member, and an element on the loom frame adapted to be engaged by said member as the heddle frame moves.

12. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked, said means comprising a member mounted for movement with the heddle frame and movable relative to the detector bar, and also with the latter during its detecting movement, means on the loom frame adapted to be engaged as the heddle frame moves in one direction to impart a detecting movement to said bar and to move said member, and an element on the loom frame adapted to be engaged by said member as the heddle frame moves in the opposite direction.

13. In a warp stop motion for looms, the combination with a heddle frame having a series of heddles supported by warp threads, of a movable detector bar mounted in the

heddle frame, the heddles being formed to engage and lock the bar against movement when a warp thread breaks, and means adapted to stop the loom when the detector bar is locked, said means comprising a member mounted for movement with the heddle frame and pivotal movable relative to the detector bar, and also with the latter during its detecting movement, means on the loom frame adapted to be engaged as the heddle frame moves in one direction to impart a detecting movement to said bar and to move said member, and an element on the loom frame adapted to be engaged by said member as the heddle frame moves in the opposite direction.

14. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked, said means comprising a pair of vertically spaced engageable elements mounted on the loom independent of the heddle frame, means mounted for movement with the heddle frame and movable thereon adapted to engage said elements, one of said elements being adapted to impart a detecting movement to the bar and the other being adapted to be engaged by said means on the heddle frame to stop the loom when the bar is locked.

15. In a warp stop motion for looms, the combination with a heddle frame having a series of heddles, supported by warp threads, of a movable detector bar mounted in the heddle frame, the heddles being formed to engage and lock the bar against movement when a warp thread breaks, and means adapted to stop the loom when the detector bar is locked, said means comprising a pair of vertically spaced engageable elements mounted on the loom independent of the heddle frame, means mounted for movement with the heddle frame and movable thereon adapted to engage said elements, one of said elements being adapted to impart a detecting movement to the bar, and the other being adapted to be engaged by said means on the heddle frame to stop the loom when the bar is locked, said means on the heddle frame having a movement adapted to carry it into and out of position to engage the said other element and being movable by the detector bar.

16. In a warp stop motion for looms, the combination with a heddle frame having a series of heddles supported by warp threads, of a movable detector bar mounted in the heddle frame, the heddles being formed to engage and lock the bar against movement when a warp thread breaks, and means

- adapted to stop the loom when the detector bar is locked, said means comprising a pair of vertically spaced engageable elements mounted on the loom independent of the heddle frame, means mounted for movement with the heddle frame and movable thereon adapted to engage said elements, one of said elements being adapted to impart a detecting movement to the bar, and the other being adapted to be engaged by said means on the heddle frame to stop the loom when the bar is locked, said means on the heddle frame having a movement adapted to carry it into and out of position to engage the said other element and being movable by the detector bar and relative thereto.
17. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked, said means comprising a pair of vertically spaced engageable elements mounted on the loom independent of the heddle frame, means mounted for movement with the heddle frame and movable thereon adapted to engage said elements, one of said elements being adapted to impart a detecting movement to the bar, and the other being adapted to be engaged by said means on the heddle frame to stop the loom when the bar is locked, said means on the heddle frame having a movement adapted to carry it into and out of position to engage the said other element, and being movable through the detector bar, and means for vertically adjusting said elements relative to one another, whereby to vary the point of contact of said means on the heddle frame therewith.
18. In a warp stop motion for looms, the combination with a heddle frame having a series of heddles supported by warp threads, of a movable detector bar mounted in the

50 heddle frame, the heddles being formed to engage and lock the bar against movement when a warp thread breaks, and means adapted to stop the loom when the detector bar is locked by a fallen heddle, said means comprising a pair of vertically spaced elements mounted on the loom independent of the harness frame, one of said elements being yieldable and having connections therewith whereby to effect stoppage of the loom when said element is moved, means movable with the heddle frame and relative thereto and to the detector bar adapted to engage one element to give the bar a detecting movement and to engage said last mentioned element when the detector bar is locked, said means being movable with the detector bar into and out of position to engage said last mentioned element.

55 19. In a warp stop motion for looms, the combination with a heddle frame having a series of heddles supported by warp threads, of a movable detector bar mounted in the heddle frame, the heddles being formed to engage and lock the bar against movement when a warp thread breaks, and means adapted to stop the loom when the detector bar is locked by a fallen heddle, said means comprising a pair of vertically spaced elements mounted on the loom independent of the harness frame, one of said elements being yieldable and having connections therewith whereby to effect stoppage of the loom when said element is moved, means for vertically 60 adjusting said elements relative to one another, means movable with the heddle frame and relative thereto and to the detector bar adapted to engage one element to give the bar a detecting movement and to engage said last mentioned element when the detector bar is locked, said means being movable with the detector bar into and out of position to engage said last mentioned element.

65

70 In testimony whereof I have hereunto set my hand.

HARRY E. KHOURY.
